UNITED STATES PATENT OFFICE.

ARTHUR O. DUPUY, OF CLEVELAND, OHIO, ASSIGNOR TO THE C. C. BARTLETT & SNOW COMPANY, OF CLEVELAND, OHIO, A CORPORATION OF OHIO.

CONVEYING MECHANISM.

1,123,000.

Specification of Letters Patent.

Patented Jan. 5, 1915.

Application filed July 22, 1913. Serial No. 780,471.

To all whom it may concern:

Be it known that I, ARTHUR O. DUPUY, a citizen of the United States, and a resident of Cleveland, county of Cuyahoga, and State of Ohio, have invented a new and useful Improvement in Conveying Mechanism, of which the following is a specification, the principle of the invention being herein explained and the best mode in which I have 10 contemplated applying that principle, so as to distinguish it from other inventions.

The subject of the present invention is a new and improved cable conveyer adapted particularly to use in connection with carrying brick, although it is of course by no 15 means limited to such a use, as will be readily seen from the following description of the same.

To the accomplishment of the foregoing 20 and related ends, said invention, then, consists of the means hereinafter fully described and particularly pointed out in the claims.

The annexed drawings and the following 25 description set forth in detail certain mechanism embodying the invention, such disclosed means constituting, however, but one of various mechanical forms in which the principle of the invention may be used.

30 In said annexed drawings:—Figure 1 is a plan view of a conveying mechanism in which my invention is embodied; Fig. 2 is a side elevation of the same; Fig. 3 is an end elevation of said mechanism; and Fig. 35 4 shows a detail of the construction.

It is customary in handling brick which have just been pressed in the usual pressing machine to convey the same upon a straight, horizontally moving conveyer consisting of 40 a plurality of cables, usually two, operating over vertically mounted and alined sheaves and to transfer the pallets upon which the molded brick are placed from the main conveyer to a suitable transverse conveyer 45 which will remove the same to the drying rooms where the pallets may be lifted from the conveyer and placed upon suitable shelves, usually formed of steam pipes, upon which the bricks are left to dry during a 50 considerable period.

It is usual for the operator who removes the pallets upon which are the newly molded brick to place a pallet upon a returning conveyer, thus always providing a supply 55 of pallets at the press. The pallets as they

are moved into the drying room are placed transversely of the cables, as they are more easily lifted from the cables when so placed, but in returning the empty pallets to the press it is immaterial whether they are disposed transversely or longitudinally on the cables, and in order to permit the shelves in the drying room to be located closer to the conveyer, it is usually desirable to return the pallets longitudinally and to narrow the space between the two cables which are used. It is, of course, an easy matter to lead the outgoing cables around a plurality of suitably disposed sheaves so that these cables will return below the outgoing cables and closer to each other, but it has been found that if the cables are continually bent, as they must necessarily be if they are led over a number of sheaves in order to narrow the space between them on their return, that they wear very rapidly and break after a short period of use.

The present invention, therefore, has to do with means for returning the cables, which are continuous, at a lower elevation 80 than the outgoing cable and closer together, thus permitting a much closer spacing of the conveyer to the shelves in the drying room, and at the same time lengthening the life of the cables by several years.

In Fig. 1 I show the main conveyer consisting of cables 1 and 2 which are suitably supported and operated over the upper surfaces of vertically disposed but horizontally alined sheaves 3, such sheaves being rotatably mounted in pairs upon suitable standards or brackets. The cables 1 and 2 which operate over the sheaves in the main conveyer are of course continuous, and are returned at a lower elevation but vertically 95 beneath the outgoing part of the cable. The drying rooms are located at one side of the main conveyer, and a transverse conveyer is provided for each room, such conveyer being substantially at right angles to the main 100 conveyer, and consisting of horizontally alined brackets or standards 5, upon the upper outer sides of which are mounted rotatably pairs of sheaves 7, over which operate continuous cables 22.

A right-angle gravity conveyer or roll 4 is provided at the intersection of the main and transverse conveyers and is adapted to receive the pallets moving on the main conveyer and to transport the same onto the 114

transverse conveyer while maintaining the pallets transversely of the latter conveyer. The construction of this gravity roll is of little importance in the present connection, but it may be described briefly as consisting of two curved downwardly extending tracks 9 and 10 suitably connected together and provided with a plurality of ball bearing wheels or rollers 11 upon which the pallet is adapted to roll.

At the outer end of the transverse conveyer there are mounted means for leading the cables beneath and vertically between the outgoing cables, such lower cables serving to return the pallets to the main conveyer in a manner which will hereinafter be described. Upon the inner sides of the brackets are other sheaves 8 spaced from each other but closer together than the sheaves 7 in the upper line.

Instead of using a number of variously disposed sheaves to direct or lead such cables to the returning sheaves 8 which are rotatably mounted upon the inside of the brackets 5, I provide a single pair of comparatively large sized sheaves 20 which are mounted at an oblique angle to the plane of the outgoing conveyer and have their upper surfaces substantially in line with the upper surfaces of the upper or outgoing sheaves, such large sheaves having their lower surfaces substantially in line with the upper surfaces of the lower lines of sheaves, and it will be noticed that such end sheaves are disposed at a substantial distance from the nearest of the sheaves in the brackets.

The cables are returned upon the lower sheaves, the brackets being provided with angle irons 12 which are mounted parallel and horizontally alined with the returning cables, such angle irons serving to keep the pallets in position upon the cables and to prevent the same from sliding off the cables at any point in the returning line. The returning cables are directed downwardly at a point adjacent to the main conveyer, and a gravity roll 13 is provided to receive the pallets and to transfer the same to the returning main conveyer, the cables on the transverse conveyer being led over sheaves 14 at the other side of the said conveyer.

The sheaves 14 are of large size and are placed vertically in order that they may be simultaneously operated by a single shaft 21. These sheaves are spaced at the same distance from each other as the sheaves 7 and are alined therewith. It is therefore necessary to provide means for leading the cables 22 from the nearest adjacent pair of sheaves in the lower line to the lower surfaces of the sheaves 12. In order to prevent any sharp bends in the cables the sheaves 14 are placed at a considerable distance from the end sheaves 24 in the lower line and a single pair of sheaves 25 is disposed be-

tween the sheaves 14 and the sheaves 24. By the provision of this long lead the cables are safely led from sheaves 24 to sheaves 14 without any sharp bends and with the use of only one intermediate pair of sheaves.

The gravity roll 13 which is disposed at this point in the transverse conveyer is straight and consists of two tracks 15 each having a plurality of rollers 16 disposed thereon, there being a short upper framework attached to the tracks, such framework also carrying rollers 16 slightly spaced from the lower rollers but alined therewith. The upper and lower rollers are spaced to permit a pallet to just pass therebetween and serve to maintain the pallet in a substantially horizontal position until the same has been shot out over the returning cables of the main conveyer. The gravity roll is at an angle adapted to give the returning pallets sufficient speed to carry them across the main conveyer and against a bumper or stop 18. Upon striking this stop the pallets drop downward upon the returning cables of the main conveyer and are thus returned to the press where they may be either removed by an operator or stacked by suitable mechanism for further use.

The operation of the device will be clear from the foregoing description, but it may be advisable to briefly summarize the operation at this point. Each pallet 17, as it is carried by the main conveyer, extends transversely of the same and on its upper surface carries a number of newly molded brick 27. This pallet with its load is shunted to a transverse conveyer but is maintained in the same position with respect to the cables of the latter, so that as it passes into the drying room an operator may conveniently grasp either end of the pallet and place the same upon the shelves in the drying plant. After he has placed a loaded pallet on the shelves he places an empty pallet between the angle irons in the lower part of the standards through which the cables pass, and this pallet is picked up and is carried longitudinally by the returning cables until it strikes the gravity roll which controls its passage onto the returning cables of the main conveyer.

It has been found that by returning the cables of the transverse conveyer in the present manner, and by thus eliminating all laterally disposed sheaves to direct the cables, that the life of the cables has been very materially increased, there being but slight wear on the same and no strain except in one direction. It is, of course, well known that a cable or wire will stand considerable strain and bending so long as the strain which is impressed upon the same is not reversed too far. The present invention takes this well known fact into account, and the cables are never bent reversely nor

sharply, which is the cause of their increased life.

Other modes of applying the principle of my invention may be employed instead of 5 the one explained, change being made as regards the mechanism herein disclosed, provided the means stated by any of the following claims or the equivalent of such stated means be employed.

10 I therefore particularly point out and distinctly claim as my invention:—

1. In a cable conveyer, the combination with a plurality of pairs of sheaves, the sheaves in each of such pairs being spaced a given 15 distance apart, two continuous cables operating in parallel on said sheaves, and other pairs of sheaves disposed in a line substantially parallel to the line of said first-named sheaves, the sheaves in each of such last- 20 named pairs being spaced a less distance than the sheaves in such first-named pairs; of two sheaves, each being disposed to have one face in line with the operating face of said first-named and said last-named 25 sheaves, said two sheaves leading said cable from said first-named to said last-named sheaves.

2. In a cable conveyer, the combination with a plurality of sheaves disposed in two 30 parallel horizontal lines, the sheaves being vertically disposed, two continuous cables operating over the upper sides of said sheaves, and a plurality of other sheaves also disposed in two horizontal lines, the 35 plane of such two lines being parallel to the plane of such first-named two lines, said second lines being disposed below and vertically between such first two lines; of two sheaves mounted at the end of such four 40 lines, each of said two sheaves having its upper surface substantially alined with the upper surfaces of one of said first-named lines of sheaves and its lower surfaces substantially alined with the upper surfaces of 45 the corresponding last-named line of sheaves.

3. In a cable conveyer, the combination with two parallel lines of sheaves, the sheaves in one of said lines being more 50 widely spaced than those in the other lines, continuous cables leading over said two lines of sheaves, and means adapted to return said cable from one end of one line to the corresponding end of said other line; of

another pair of sheaves disposed at the 55 other end of said lines, said sheaves being alined with the sheaves in said widely spaced line, and a pair of sheaves disposed between said other sheaves and the nearest adjacent sheaves in said narrowly spaced 60 line, said cables returning from one line of sheaves to the other over said other and said last-named sheaves.

4. In a cable conveyer, the combination with two parallel lines of sheaves, the 65 sheaves in one of said lines being more widely spaced than those in the other lines, continuous cables leading over said two lines of sheaves, and means adapted to return said cables from one end of one line to 70 the corresponding end of said other line; of another pair of sheaves disposed at the other end of said lines and spaced a considerable distance from the nearest pairs of sheaves in said two lines, said last-named 75 pair of sheaves being alined with the sheaves in said widely spaced line, and a pair of sheaves disposed between said other sheaves and the nearest adjacent sheaves in 80 said narrowly spaced line, said cables returning from one line of sheaves to the other over said other and said last-named sheaves.

5. In a cable conveyer, the combination with two horizontally disposed lines of sheaves, one above the other, the sheaves being disposed in pairs and the sheaves in the upper line being more widely spaced than those in the lower line, continuous cables leading over said two lines of sheaves, and means adapted to return said cables from 90 said upper line to said lower line; of a pair of sheaves disposed at the other end of said lines and a considerable distance therefrom, said end sheaves being alined with said widely spaced sheaves in said upper line; 95 and another pair of sheaves disposed between said end sheaves and said lines, said last-named sheaves being spaced a less distance apart than said widely spaced sheaves and a greater distance than said narrowly 100 spaced sheaves and being adapted to lead said cables from said lower sheaves to said end sheaves.

Signed by me, this 19th day of July, 1913.

ARTHUR O. DUPUY.
